FIG. 1 is a perspective view of a connecting ring for water spraying head showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective schematic view illustrating an applica-
tion of a connecting ring for water spraying head showing
my design;
FIG. 9 is another perspective schematic view illustrating another
application of a connecting ring for water spraying
head showing my design; and,
FIG. 10 is another perspective schematic view illustrating a
different application of a connecting ring for water spraying
head showing my design.
The broken line is included for the purpose of illustrating
environmental structure and forms no part of the claimed
design.
